WIRE COILING AND SIZING MACHINE

John O. Forster, Long Island City, N. Y., assignor,
by mesne assignments, to Heli-Coil Corporation,
Long Island City, N. Y., a corporation of Dela-
ware

Application February 7, 1948, Serial No. 6,902

5 Claims. (Cl. 153—2)

1

The invention relates to a machine for coiling wire and sizing it as to its cross-sectional shape in the finished coil in the production of exact screw-thread inserts or coil springs. With the aid of conventional machines, it is practically impossible to overcome the effects of the bending stresses which cause uncontrollable deformations of the wire cross-section. In consequence, wire coils produced by such conventional machines show marked differences in the cross-sections, not only of the wire before and after the coiling, but also of the wire in different specimens of coils of the same size and made of the same stock. The main cause of this occurrence can be traced back to differences in the structure of the material, but other influences, not readily explained, seem to contribute thereto. In fact, in order to attain a reasonably large percentage of saleable coils out of a total output of allegedly exact coils made on conventional machines, tolerances must be conceded which frequently render the product unsuited for application in high precision work.

The present invention aims to provide a machine by means of which wire coils can be turned out in an unusually high grade of perfection.

The invention also aims to provide such a machine in which finished coils of desired length can be severed from the wire stock without interruption of the coiling operation.

The invention essentially comprises a mandrel rotatable between three rollers, the mandrel and two of the rollers being provided with grooves according to the desired wire cross-section and arranged in the same plane. The mandrel and two grooved rollers are positively driven, to shape wire from a stock by passing it through the grooves between the rollers and the mandrel, and means are provided to apply a pitch to the wire convolutions formed by the rotating parts.

The invention also consists in means to notch the wire at adjustably predetermined intervals before it enters between the mandrel and rollers, so that it breaks at the notched points when the wire near these points is subjected to the bending effect of the pitching means.

Further objects and details of the invention will be apparent from the following description and the accompanying drawing illustrating an embodiment thereof by way of example. In the drawing,

Fig. 1 is a front elevation of a machine according to the invention;

Fig. 2 is a top plan view thereof;

2

Figs. 3 and 4 are cross-sections along lines 3—3 and 4—4, respectively, of Fig. 1;

Fig. 5 is a cross-section along line 5—5, in Figs. 2 and 4, the gears driving the mandrel being omitted in Fig. 5;

Fig. 6 is a cross-section along line 6—6 of Fig. 2;

Fig. 7 is an illustration of formation of the coil;

Fig. 8 is a cross-section of the notching roller along line 8—8 of Fig. 1;

Fig. 9 illustrates, in elevation, the separation of a formed coil;

Fig. 10 is a top plan view of a solenoid-controlled and timed drive for the notching roller; and

Fig. 11 is a side elevation of the cam detent thereof.

Referring now to the drawing, the machine comprises a base plate 10 having feet 11 to stand it on a table or other support (not shown). A front plate 12 and a rear plate 13 are secured to the base plate by means such as screw bolts 14 in upright position. All tools acting on the wire 15 to be coiled are arranged in front of the front

plate. Only a short portion of wire 15 is shown in Fig. 1 in order to avoid overcrowding of the drawing. The driving gear of the movable tools are located between the front and rear plate and in the rear of the latter. The tools comprise a

mandrel 16, a coiling roller 17, a sizing roller 18, a pitch member 19, and a notcher 20. Power to operate the machine is derived from the main shaft 21 which may be driven by any suitable and conventional means, either by a prime mover or

20 a hand crank as shown at 22 in Fig. 4. The main shaft is journaled in a flanged bushing 23 secured in the rear plate 13 by means such as

23 screws 24. A gear wheel 25 keyed to the front end of the main shaft engages another gear wheel 26 to which a third wheel 27 is rigidly connected for

30 common rotation by an intermediate piece 28 and screw bolts 29. Wheels 26 and 27 can rotate on a bushing 30 mounted on a sleeve 31 which is keyed to a counter shaft 32 journaled in bushings 33 and 34 of the front and rear plates, re-

35 spectively. Wheel 27 engages a pinion 35 (Fig. 3) keyed to the mandrel shaft 36 which rotates in

needie bearings 37 and 38. These bearings are

40 parts of straps 39 and 40, respectively, which can

45 swing on bushings 41 and 42 mounted on sleeve

31 in order to maintain the correct distance of

50 the centers of wheel 27 and pinion 35 when the mandrel shaft is to be adjusted as it will be explained hereinafter. The position of the rear

55 mandrel end is rendered adjustable by two screws

43 and 44 bearing on the bottom and top, respectively, of that end of strap 40 which contains the needle bearing 38. Screw 43 engages an inner threading of the head 45 of a bolt 46, the shaft of which extends through the rear wall 13 and is secured to it by a nut 47. A jam nut 48 on screw 43 insures the adjusted position. The arrangement of screw 44 engaging the head of a bolt 49 is similar to that of screw 43. The front portion of the mandrel shaft 36 extending close to the front wall 12 is hollow at 50 (Fig. 3) to receive therein an enlarged rear end 51 of the mandrel 16. In order to render the mandrel exchangeable and also to make it adjustable lengthwise, it is fastened to the shaft 36 by means of a groove 52 and set screw 53 connection. The mandrel 16 extends forward of the front wall 13 through a hole 54 therein which is considerably larger than the diameter of the mandrel to allow for an adjustment of the latter. The mandrel front end is provided with a peripheral groove 55 of a cross-section according to the desired shape of the inner portion of the wire in the coil to be formed.

The coiling roller 17 bearing from below against the mandrel or against a wire between the roller and the mandrel has a peripheral groove 56 and is so located that groove 56 and the mandrel groove 55 are in the same plane. Groove 56 may be slightly wider than the desired outer portion of the wire in the finished coil as the actual sizing will take place between the mandrel and the sizing roller 18. But the groove 56 should be narrow enough to take along the wire coming from the stock and to coil it as hereinafter explained. The roller 17 has a second groove 57 which may or may not be of the same shape as groove 56 either for use if groove 56 is worn or if a differently shaped wire is to be coiled. By loosening the set screws 53 and shifting the mandrel in shaft 36, grooves 55 and 57 may be brought in registry. It is of course also possible to provide more than one peripheral groove on the mandrel for the same purpose as there are two grooves in the periphery of roller 17. Roller 17 is mounted adjustable in a vertical direction. Such adjustability is desirable on the one hand to set the desired pressure between the roller and the mandrel, on the other hand to allow for the possibility of using rollers of different sizes. For this purpose, the front wall 13 is provided with a rectangular recess 58 in which a bearing block 59 is slidable. The block overlaps the recess in front and has guide rails or pieces 60 in the rear of the front wall in order to hold the block properly in relation to the wall. Underneath the block a piece 61 interiorly threaded at 62 is fastened to the frame consisting of the base plate 10 and the front and rear walls 12 and 13. A screw 63 on which block 59 bears is screwed through the threading 62, and extends through a hole 64 in the base plate. Underneath the latter, a hand wheel 65 is fastened to screw 63 by means of a set screw 66, so that by turning the wheel, block 59 will either be shifted upward or allowed to slide downward as the case may be. In its upper part, block 59 contains two roller bearings 67 and 68 for a shaft 69 to the front end of which the coiling roller 17 is secured by means of a key 70 and nut 71. A pinion 72 is fastened by a pin 73 to the rear end of the shaft 69 and engages another pinion 74 (Figs. 1 and 4) rotatable on a bushing 75 mounted on an axle 16. This axle can be shifted for adjustment in an arcuate slot 77 of the front wall 12 and clamped to that

wall by a spacer 78 and a nut 79 on the threaded front end 80 of the axle. Pinion 74 is in mesh with a wheel 81 on a shaft 82, while another wheel 83 on that shaft is in mesh with a wheel 84 keyed to the countershaft 32. In order to insure proper meshing of the gears when shaft 69 is shifted, the aforementioned spacer 78 is in the form of a strap which can swing about shaft 82. In order to rotate the countershaft 32, there is a gear 85 keyed to the main shaft 21 and in mesh with a gear 96 on an intermediate shaft 94 from where rotation is imparted to the countershaft by a pair of meshing pinions 92 and 93 keyed to the countershaft 32 and shaft 94, respectively.

The sizing roller 18 is provided with a peripheral groove 90 in the same plane as groove 55 of the mandrel and groove 56 of the coiling roller. The shape of the cross-section of groove 90 is such that it exactly complements that of the mandrel groove to the desired cross-section of the wire in the finished coil. A second groove 91 may be provided in the periphery of roller 18 for the same purpose as the second groove 57 of roller 17. Roller 18 is shown of a smaller size than roller 17. This, however, is not necessarily so, as the relative circumferential speeds of the rollers rather than their sizes have certain effects in the coiling and sizing of the wire. Roller 18 is driven by the gears 85, 96 and 97, the latter being keyed to a shaft 95. A pinion 98 on shaft 95, finally, meshes with a pinion 99 on a shaft 100 to which the sizing roller 18 is also keyed and held in position by a nut 101. All the mentioned shafts 94, 95 and 100 are journaled in the frame front and rear walls 12 and 13.

Means are provided to counteract the pressure exerted by the coiling and sizing rollers on the mandrel. For this purpose, a clamping member 102 is secured to the front plate 12 so as to project forward thereof. A screw 103 with forked head 104 is adjustably held by member 102 and can be secured by a clamping screw 105 and two nuts 106 and 107 on the threading of screw 103. In the forked head 104 a pressure roller 108 is pivoted on a pin 109 and bears against the mandrel 16 so as to balance the resultant of the pressure of the coiling and sizing rollers.

The pitching tool 19 has an active end face 110. This face is inclined with respect to the plane of the cooperating roller and mandrel grooves and so positioned in the path of a wire coil convolution having left the sizing roller, that the face 110 deflects the convolution to provide it with the desired pitch. The shaft 111 of the pitching tool is adjustably held by a two-part clamp 112, 113 (Fig. 4) in which it can be shifted lengthwise and also turned. Two screws 114 furnish the clamping force and simultaneously serve to secure the clamp to the head 115 of a screw bolt 116 which is screwed into and projects forward of the front plate 12. A jam nut 117 secures the bolt and prevents it from undesired turning.

In order to lead the wire 15 from a stock to the mandrel in the plane of the roller grooves, a guide 118 of conventional type may be provided which has an inner cross-section 119 according to the wire cross-section prior to the coiling. The guide 118 is secured to the front wall 12 by screws 120. It conducts the wire so as to be tangent with respect to the mandrel at a point slightly spaced from the point of tangency of the mandrel and the coiling roller 17. As the wire is pulled through the machine by

the coiling and sizing rollers in co-operation with the mandrel, irregularities may occur due to more or less slack of the wire coming from the stock. In order to avoid such irregularities, it is advisable to apply means for giving the wire a certain constant adjustable tension. For this purpose a pair of tension rollers 121 and 122, one above the other and spring loaded against each other are provided, which are peripherally grooved as at 123 so that the wire from the stock can be passed between the rollers. For the same reason as explained with respect to rollers 17 and 18, the tension rollers may have additional grooves such as 124. The lower roller 121 is journaled on an axle 125 secured to the front plate 12 by any suitable means. The upper roller 122 is fixed to a shaft 126 the front portion of which is journaled in a block 127 of a structure similar to the bearing block 59 of the coiling roller 17. Block 127 is vertically slidable in a recess 128 of the front plate. A screw 129 engages an interior threading of a part 130 of the front plate bridging the recess 128, and bears on a spring 131 which in return presses on block 127. Thereby the pressure exerted by the rollers 121 and 122 on the wire and thus the friction between them can be adjusted. The rear end of shaft 126 has its bearing 132 in the rear plate 13. This bearing must have sufficient play to allow for the very slight misalignments of the shaft which may occur owing to an adjustment of the block 127. Adjacent the rear plate, shaft 126 may be provided with a brake of any suitable and conventional type, comprising, for instance, a drum 133 and brake band 134 encompassing the major portion of the drum periphery. The drum is keyed to the shaft by a pin 135 and the one end 136 of the band 134 is secured to the rear plate by a pin 137. The other end of the band is fastened by means not shown to a screw 138 which is passed through an eye 139 projecting forward from the rear plate 13. A nut 140 on screw 138 and bearing against the face of the eye serves to adjust the braking force applied.

To produce continuous coils of exactly sized wire cross-section, the machine so far described operates in the following manner: The free end of wire 15 of a cross-section more or less similar to that desired in the finished coil, but preferably slightly larger in its cross-sectional area, is passed from a stock not shown from the left hand side of Fig. 1, between the back tension rollers 121, 122, through the guide member 118 and from there first between the mandrel 16 and coiling roller 17 and, then, between the mandrel and the sizing roller 18, and finally past the inclined face 110 of the pitching tool so that the free end of the wire is slightly bent forward in relation to the groove plane of mandrel and rollers. If, now, the main shaft 21 is rotated in the direction of the arrow *a* in Fig. 1, a continuous coil will be formed as indicated at 200, in Fig. 7, the diameter of which will depend on that of the mandrel and the property of the wire material and shape of the wire cross-section. The correct mandrel diameter for a given wire material and desired coil diameter and cross-section must be found by trial, i. e. by changing the mandrel in shaft 36. If this is done, adjustments are required, as the location of the axis of the sizing roller is fixed. Adjustments of the mandrel axis will be made by turning the screws 43 and 44 in the proper direction; by means of

5 wheel 65 the axis of the coiling roller is to be raised or lowered as the case may be; simultaneously, the shaft 80 will be shifted in slot 71 in order to cause proper mesh of wheels 72 and 74; and finally the pressure roller 108 will be set by correcting the position of the screw shaft 103 in clamp 104. Also the pitching tool 19 may require a readjustment in its clamp 113, and it may become necessary to alter the tension of the brake band 134 by turning the nut 140. Once, however, the setting has been finished, the machine will turn out a continuous wire coil of excellent uniformity and accuracy of the cross-section. It is to be noted, however, that best results will be obtained if the peripheral speed of the coiling roller is higher than that of the mandrel, and the peripheral speed of the sizing roller higher than that of the coiling roller. Such speed ratio can be obtained by a proper selection of the transmission ratios of the various gears.

Now, I have found that by a simple method and means in addition or as an attachment to the machine described, coils of desired length rather than a coil of continuous length may be produced. The principle according to which this can be done consists in that the wire coming from the stock, and before being subjected to the coiling operation, is notched in predetermined equal intervals according to the desired length of the coils. When the notches are sufficiently deep and of adequate shape, it can be attained that the effect of the pitching, that means the bending of the coiled wire out of its original plane will cause the wire to break at the notch. This is clearly shown in Fig. 9 (see also Fig. 7) where the break occurs at the point 300 when the notched portion of the wire coming from between roller 18 and mandrel 16 engages the inclined face 110 which bends the coil portion preceding the notch out of axial alignment with the subsequent portion 392. Even if the wire is relatively very deeply notched a premature break during the coiling and sizing need not occur, if, as it is the case in the described machine, the wire is taken along rather than pushed through the coiling device, due to the fact that the wire is positively fed through coiling roller and mandrel and sizing roller and mandrel. Of course, in the notched wire cross-section, the remaining material must be of sufficient strength to pull the following wire stock through the apparatus including the tension rollers, if such are present, until the wire portion following a notch is gripped between the mandrel and the coiling roller. It also should be able to withstand the tension of the wire between the coiling and sizing roller owing to their speed difference. In view of the stress distribution during the coiling, it is advisable to make the notch in that portion of the wire which becomes the inner portion in the coil.

In the illustrated embodiment, a notching device comprises a pair of rollers 150 and 151 which are located between the tension rollers 121, 122 and the wire guide 118. The rollers 150, 151 of the notching device may be located on the opposite side of rollers 121, 122. However, the illustrated arrangement is preferable because there will not be any slack in the wire having passed the tension rollers. Otherwise, a slack might be the cause of irregularities in the lengths between subsequent notches. Both rollers 150 and 151 are peripherally grooved, the groove of the upper roller 151 being visible in Fig. 2 at 152. In the

7
illustrated embodiment, only roller 151 is provided with the notching element whereas roller 150 serves to support the wire during the notching. Of course, if it is desired to notch the wire from the opposite side, both rollers may be equipped with such elements. As clearly shown in Fig. 8, the notching roller 151 comprises two disc parts 200 and 201 fitted together and so peripherally recessed as to form the afore-mentioned groove 162. Dowels 202 and screws 203 hold the parts so together that radial grooves, one of them in each of the parts 200 and 201, complement each other to form a radial bore 204 of square cross-section. The above-mentioned notcher 20 consists of a piece having a head portion 205 which is of square cross-section and tapers from two opposite sides so as to form a notching or cutting edge 162. The shank 207 of the notcher is externally screw-threaded and the piece 20 is so fittingly but slidingly inserted in the bore 204 that the edge 162 is transverse in relation to the peripheral groove 162 and may be adjustably projected or retracted. For this purpose an oblong slot 208 is provided in the discs in a plane at right angles to the radial bore 204, and a nut 209 turnably inserted in the slot 208 engages the threaded shank 207 of the notcher. Hence, by turning the nut 209 the notcher 20 can be raised or lowered, that means more or less projected, as the case may be. A set screw 210 may be applied in one of a number of threaded holes 211, whichever may be suitably located, and which holes are provided in nut 209 for this purpose. More than one notcher may be provided in one notching roller, depending on whether only one or several notches are intended to be made per each revolution of the notching roller. The second slot 212 visible in the roller 152 in Fig. 1 indicates that in this particular embodiment, the roller can accommodate two notchers spaced 180 degrees.

The rollers 150 and 151 may be journaled similarly to the rollers 121 and 122, respectively. Thus, whereas the axis of the lower roller 150 is fixed, roller 151 has its front bearing in the block 153 which is vertically shiftable in a recess 154 of the front plate. A screw 155 is screwed through the aforementioned bridge portion 130 which also bridges recess 154, and is secured to the front plate 13 by a screw bolt 156. Screw 155 bears on block 153 so that by turning the screw the pressure exerted on the wire 15 between the rollers 150 and 151 can be adjusted. A set screw 157 may be provided to insure an adjusted position of screw 155. The notching device just described has the effect that each time the edge 162 engages a wire piece between rollers 150 and 151, a notch will be made and the notches will be spaced from one another a distance equal to the length of the periphery of roller 151. If, then, a wire portion sufficiently notched in this manner has passed the coiling and sizing rollers and comes with the notch in the range and under the effect of the pitching tool 19, the wire will break and coils of equal length will be produced. The same or a similar notching device can of course be used if it is the intention to provide a continuous coil merely with notches without severing it into coils of a predetermined length. In that event, the notches will be made shallower by a suitable adjustment of the notcher 20 so that the bending effect of the pitching tool is insufficient to cause a break.

It will be noted that in the described device the notching roller 151 relies for rotation on the

5 positive drive and the gear reductions in the machine hereinbefore described. In consequence, if it is desired to change the coil length, it is necessary to change roller 151, and if coils of considerable length are required, it may happen that the structure cannot accommodate a roller 151 of sufficiently large diameter. These drawbacks are avoided in the modification of Fig. 10 in which a timing or measuring device for the notching is provided in order to operate a notching roller each time a certain length of wire has passed an organ which is responsive to the wire movement. In this device, adjustability exists within wide limits.

10 Fig. 10 shows merely that portion of the machine which comprises the tensioning rollers and the notching roller. The coiling and sizing apparatus with transmissions and other accessory parts have been omitted and with respect to them reference is made to the preceding description. Also in the illustration of the tensioning and notching rollers certain parts appearing on Figs. 1 and 2 have been omitted in order not to over-crowd Fig. 10 with repetitions. Thus, in connection with the tensioning roller, the braking mechanism, and in connection with the bearing blocks 121 and 123, the means for adjusting the pressure have not been shown again. Whereas with respect to the tensioning rollers the arrangement may be like that in Figs. 1 and 2, the notching roller 151 is power driven. For this purpose a gear wheel 170 is keyed by pin 171 to the roller shaft 172. (The location of gear wheel 170 has also been indicated in Fig. 2). Wheel 170 meshes with a gear wheel 173 which is integral with a short shaft 174 journaled with its one end in a bushing 175 in the front plate 12 of the frame and, intermediate wheel 173 and its other end, in a bearing 176 erected on the base plate 10. To the rear end of shaft 174, the driven part 177 of a friction clutch is keyed, and between that part and bearing 176, a cam 178 is secured to the shaft. As clearly shown in Fig. 11, the cam is essentially circular except for a peripheral projection 179 which forms a step 180 for a purpose to be explained hereinafter. A shaft 181 is journaled co-axially with shaft 174 in a bearing 182 and a bushing 183 in the rear wall 13. The driving part 184 of the mentioned friction clutch is splined to the front end of shaft 181 and the conventional friction discs 185 are provided between parts 177 and 184. A compression spring 186 bears against part 184 and a collar 187 secured to shaft 181. The rear end of shaft 181, projecting from rear wall 13, carries a gear wheel 188 which is in mesh with a pinion 189 on the shaft 190 of a constant speed motor 191. Any other suitable prime mover may be used to rotate the shaft 181. Thus it is also possible to drive this shaft from the same source as the main shaft 21 in Fig. 2.

15 The armature 192 of a solenoid 193 co-operates with cam 178 in such a manner that if the armature is projected by a compression spring 194 bearing against the solenoid and a collar 195 of the armature, it engages the step 180 and thus prevents shaft 174 from rotating. The solenoid is electrically connected by leads 196, 197 to a timing mechanism 198. The timing mechanism proper is no part of the present invention, and as various types of such mechanisms useful for the purpose are on the market it suffices to state its function rather than its structure. The timing mechanism is, generally speaking, a switch closing a contact each time an organ of the

mechanism has traveled a predetermined distance, as e. g. a rotatable member causing operation of the switch each time it has completed a certain number of revolutions for which the mechanism can be set by the user. In Fig. 10 the mentioned organ or rotatable member is a shaft with a roller 199. The arrangement is such that roller 199 bears on wire 15 coming from the stock and running in between the tensioning rollers 121, 122. Any support not shown may be used for the wire so that the friction between the wire and roller 199 will cause the latter to rotate according to the wire length passing underneath the roller 199. Each time when a desired number of roller revolutions for which the timing mechanism has been set has been completed, the solenoid circuit from + to 198, 197, 193, 196, 198 and — will be closed so as to withdraw the armature from step 180. In consequence, the constantly rotating shaft 181 will take along shaft 174 through the agency of the clutch 184, 185, 177 and turn the notching roller 151. Provided the timing device opens the solenoid circuit before the shaft 174 completes two revolutions, the notching roller will be stopped by armature 192 engaging the cam step 180, exactly after one complete revolution as the ratio between wheels 173 and 170 is 1:2 in the illustrated example.

The machine operates in the following manner: The wire 15 coming from the stock is passed first, between the pairs of rollers 121, 122 and 150, 151 and on through the wire guide 118. The free end is, then, passed between mandrel 16 and roller 17 and between the mandrel 16 and roller 18, and bent so that it bears on the inclined face 110 of the pitching tool. If now the machine is started, that means when shaft 21 is rotated, rotation is transmitted (see Figs. 3, 4 and 6) from shaft 21 to the mandrel 16 via gear 25, the pair of wheels 26 and 27 which are in common freely rotatable on sleeve 30 as hereinbefore explained, and pinion 35 which is in mesh with wheel 27 and secured to the mandrel shaft 36.

Simultaneously, as best seen in Fig. 5, the coiling roller 17 secured to shaft 69 is driven by shaft 21 via gears 85, 96, shaft 94, gears 93 and 92, shaft 32, gears 84 and 83, shaft 82, and gears 81, 74 and 72. Similarly, the sizing roller 18 on shaft 100 is driven via gears 85, 96, 97, shaft 95 and gears 98 and 99. Owing to the rotation of the mandrel and the coiling and sizing rollers a continuous coil will be formed to be separated into sections if the notching device 20 is in operation as hereinbefore explained.

It will be apparent to those skilled in the art that many alterations and modifications of the structure illustrated and described may be made without departing from the essence and spirit of my invention which, for this reason, shall not be limited but by the scope of the appended claims.

I claim:

1. In a machine of the type described, the combination of a rotatable mandrel, a first and a second roller having axes respectively parallel to the mandrel axis and being arranged with their peripheries in close proximity to that of the mandrel, said mandrel being positively driven in one direction, each of said rollers being positively driven in the opposite direction, said mandrel and said rollers having peripheral grooves all in one plane and of cross-sections so that the grooves of the mandrel and the first roller complement each other to a cross-section substantially similar to but slightly larger than the de- 70

sired cross-section of a wire convolution coiled by means of said machine, and that the grooves of the mandrel and the second roller complement each other to said desired cross-section, and a tool having a face inclined in relation to said plane of said grooves, and in the path of a convolution of a wire passed between said mandrel and said rollers to deflect said convolution from said plane.

5 2. A machine as claimed in claim 1, further comprising first driving means for said mandrel, second driving means to rotate said first roller at a higher peripheral speed than that of said mandrel, and third driving means to rotate said second roller at a higher peripheral speed than that of said first roller.

15 3. In a machine of the type described, the combination of a rotatable mandrel, a first and a second roller having axes respectively parallel to the mandrel axis and being arranged with their peripheries in close proximity to that of the mandrel, said mandrel and said rollers having peripheral grooves all in one plane and of cross-sections so that the grooves of said rollers complement the groove of the mandrel substantially to the desired cross-section of a wire convolution coiled by means of said machine, first driving means for rotating said mandrel in one direction, second driving means to rotate said first roller in the opposite direction and at a higher peripheral speed than that of said mandrel, third driving means to rotate said second roller in the same direction as and at a higher peripheral speed than said first roller is driven, and a tool having a face inclined in relation to said plane of said grooves and in the path of a convolution of a wire passed between said mandrel and said rollers to deflect said convolution from said plane.

25 4. In a machine of the type described, the combination of a device including positively driven elements cooperative in continuously coiling wire whereby the wire is pulled from a stock, means in the path of the wire from the stock to said device for intermittently notching the advancing wire, and means projecting in the path of the formed coils to sever them at the notches.

30 5. In a machine of the type described, the combination of a device including positively driven elements cooperative in continuously coiling wire whereby the wire is pulled from a stock, and means in the path of the wire advancing from the stock to said device for intermittently notching it, said means including a roller having a notching edge projecting from its periphery, a first shaft in driving connection with said roller, a second shaft including means for connection to a constant speed prime mover, a friction clutch between said shafts, a spring-biased detent element preventing said first shaft from rotating when in projected position, a member to withdraw said detent against the restraint of said spring, and means including an organ adapted to engage the advancing wire and responsive to lengths of wire passing it, to actuate said member each time a predetermined length of wire has passed said organ.

35 6. In a machine of the type described, the combination of a device including positively driven elements cooperative in continuously coiling wire whereby the wire is pulled from a stock, and means in the path of the wire advancing from the stock to said device for intermittently notching it, said means including a roller having a notching edge projecting from its periphery, a first shaft in driving connection with said roller, a second shaft including means for connection to a constant speed prime mover, a friction clutch between said shafts, a spring-biased detent element preventing said first shaft from rotating when in projected position, a member to withdraw said detent against the restraint of said spring, and means including an organ adapted to engage the advancing wire and responsive to lengths of wire passing it, to actuate said member each time a predetermined length of wire has passed said organ.

40 7. In a machine of the type described, the combination of a device including positively driven elements cooperative in continuously coiling wire whereby the wire is pulled from a stock, and means in the path of the wire advancing from the stock to said device for intermittently notching it, said means including a roller having a notching edge projecting from its periphery, a first shaft in driving connection with said roller, a second shaft including means for connection to a constant speed prime mover, a friction clutch between said shafts, a spring-biased detent element preventing said first shaft from rotating when in projected position, a member to withdraw said detent against the restraint of said spring, and means including an organ adapted to engage the advancing wire and responsive to lengths of wire passing it, to actuate said member each time a predetermined length of wire has passed said organ.

45 8. In a machine of the type described, the combination of a device including positively driven elements cooperative in continuously coiling wire whereby the wire is pulled from a stock, and means in the path of the wire advancing from the stock to said device for intermittently notching it, said means including a roller having a notching edge projecting from its periphery, a first shaft in driving connection with said roller, a second shaft including means for connection to a constant speed prime mover, a friction clutch between said shafts, a spring-biased detent element preventing said first shaft from rotating when in projected position, a member to withdraw said detent against the restraint of said spring, and means including an organ adapted to engage the advancing wire and responsive to lengths of wire passing it, to actuate said member each time a predetermined length of wire has passed said organ.

JOHN O. FORSTER.
